(57) **CLAIM**

An ornamental design for a cocktail shaker-shaped foil pouch, as shown and described.

DESCRIPTION

FIG. 1 is an isometric view of a cocktail shaker-shaped foil pouch showing our new design;

FIG. 2 is a front plan view thereof;

FIG. 3 is a left side elevation view thereof;

FIG. 4 is a right side elevation view thereof;

FIG. 5 is a rear plan view thereof;

FIG. 6 is a top plan view thereof; and,

FIG. 7 is a bottom plan view thereof.

That which is depicted in solid lines in the drawings represent the claimed invention and that which is depicted in broken lines forms no part of the claimed invention. FIG. 2 has opaque surface shading. FIGS. 3 and 4 each include a vertical line (part solid and part broken) that signifies a demarcation between opaque surface shading and transparent or translucent surface shading. FIG. 5 has transparent or translucent surface shading. FIGS. 6 and 7 each include a horizontal line (part solid and part broken) that signifies a demarcation between opaque surface shading and transparent or translucent surface shading.
